UNITED STATES PATENT OFFICE.

GUION THOMPSON, OF MILTON, CONNECTICUT, AND HUNTINGTON W. MERCHANT, OF NEW YORK, N. Y.

TRACK CONSTRUCTION AND ELECTRIC SIGNALING AND CONTROLLING EQUIPMENT THEREOF.

No. 923,800.

Specification of Letters Patent.

Patented June 1, 1909.

Application filed February 27, 1905. Serial No. 247,579.

To all whom it may concern:

Be it known that we, GUION THOMPSON, a citizen of the United States, residing at Milton, in the county of Litchfield and State of Connecticut, and HUNTINGTON W. MERCHANT, a citizen of the United States, residing in New York, in the State of New York, have invented certain new and useful Improvements in Track Construction and Electric Signaling and Controlling Equipment Thereof; and we do hereby declare the following to be a full, clear, and exact description of the invention, such as will enable others skilled in the art to which it appertains to make and use the same.

Our invention relates to track construction and electric signaling and controlling equipment therefor.

It has for its object the provision of means adapted to communicate to a second conveyance passing upon a portion or block of said track and equipped with a suitable electric signal-receiving device, a primary danger signal, indicating the occupancy by a similar or first conveyance of a certain portion of said track in advance of said second conveyance.

It has for a further object such arrangement and construction of said track and signal-communicating means as will adapt it at another point on said track to communicate to any passing conveyance so equipped a secondary danger signal or "fail to danger" signal, indicating, if such be the case, that the primary danger-signal communicating devices are out of order.

It has for its further object such construction of track and electric devices as will communicate such signals at respectively different points to a second and third such conveyance running in opposite directions on one track and equipped as aforesaid.

It has for a further object such construction of the electric equipment for said track as will permit it to be set for operation by a traveling contact at one point on the route of said track and afterward discontinued from operation by the action of said traveling contact at a relatively distant point on the route of said track.

With these and other objects in view, it consists of the electric circuits, constructions, combinations and arrangements of parts hereinafter described and claimed.

In the accompanying drawings, Figure 1 is a diagrammatic view of a railway track constructed and equipped in accordance with our invention, showing diagrammatically a conveyance adapted to move on said track and equipped with devices for operating and availing of said invention. Fig. 2 is a diagrammatic view of a modified form of our said invention. Fig. 3 is a diagrammatic view of another modified form of our said invention, and Fig. 4 is a diagrammatic view of a modified portion of our said invention showing means for discontinuing the electric current through the coil of the electro magnet F. Fig. 5 is a diagrammatic view of another modified form of our invention.

Describing first the form of construction shown in Fig. 1, in the accompanying drawings, to which reference is hereby made, 1 and 2 are parallel lines of rails forming a railway track, each of said lines being divided into sections in any suitable manner and by any suitable non-conductors of electricity as, in said line 1, by the insulating blocks 1^b, 1^c, 1^f and 1^g and in said line 2 by the insulating blocks 2^b, 2^c, 2^f and 2^g; thus dividing said track—considering both lines of rails taken together—into sections A, A¹, C¹ and A², of which sections those designated A, A¹ and A² will usually be much longer than the others of said sections. Whenever, as may be the case, either line of said rails of said sections A, A¹ and A² is required to carry a conveyance-driving current of electricity to or from a conveyance moving upon said rails, said line or lines of rails of said sections A and A¹ will be electrically connected with each other around section C, and by any suitable electricity-conducting means, as by the wire 3, and said section A¹ will be electrically connected to said section A² around said section C¹ and by any suitable electricity conducting means, as by the wire 3^a.

The sections C and C¹ are preferably electrically connected together in any suitable manner and by any suitable electricity conducting means, as by the wire 4, which may be connected to either line of the rails of said sections C and C¹. The sections A and C are normally electrically connected together in any suitable manner and by any suitable means including a normally closed contact, as, preferably, by portions of the wires 4 and 5 and the contact points 4^a and 5^a. The sec-

tions B¹ and C¹ are normally electrically connected together in any suitable manner and by any suitable means including a normally closed contact, as, preferably, by portions of 5 said wires 4 and 5 and by said contact points 4^a and 5^a. Stationed at any suitable place with reference to said sections, is a source of electricity of any suitable nature or construction, as for example a battery E. Positioned 10 in any suitable place adjacent to said section C, as, for example, between the lines of rails thereof, is a pair of normally open electric contacts 6 and 6^a, electrically insulated from ground, which contact 6, is electrically connected by any suitable means, as by a wire 7, and a portion of the wire 11, with one pole of 15 said battery E. The opposite pole of said battery is connected with one end of the coil of an electro-magnet F stationed in any suitable position with reference to said track, the 20 opposite or free end of which coil is provided with a contact or pole 8 of a normally open contact of which the contact 9 is the opposite pole or point. Said last referred to normally 25 open contact is adapted to be closed by the operation of an armature and armature lever 10 governed by said electro-magnet when energized, and said contact 9 is electrically connected by any suitable means, as 30 by the wire 11 with the said opposite pole of said battery E. Said contact 6^a is electrically connected by any suitable means or in any suitable manner, as by the branch wire 6^b and a portion of the wire 12 with that end 35 of said coil which is connected to said contact 8. If, therefore, the contacts 6 and 6^a are closed, or electrically connected together at any time, a closed electric circuit will be established including the contacts 6 and 6^a, the 40 wire 7, a portion of the wire 11, the battery E, the electro-magnet F a portion of the wire 12 and the branch wire 6^b. The electro-magnet will thereupon be energized and will attract said armature thus closing the normally 45 open contact of which 8 and 9 are the points. An electric circuit will thereby be closed including said battery, said coil said points 8 and 9 and said wire 11, thus maintaining the energy of said electro-magnet until 50 said last referred to circuit is broken or opened as hereinafter described. Said contact 6, or the corresponding pole of the source E, is electrically connected by any suitable means, as by a wire 13 with a contact 6^d 55 which is stationed in, or adjacent to said section C¹ and preferably near to the same line of rails as that to which said contact 6 is near. Adjoining said contact 6^d is a contact 6^e which is electrically connected by any suitable 60 means, as by a wire 14 with the battery-connected end of the coil of said electro-magnet F. Said contact 6^d is electrically connected by any suitable means as by a wire 6^f with one pole 6^g of a normally open contact, the opposite pole 6^g of which latter con-

tact is electrically connected by any suitable means, as by the wire 12 with that end of said coil which is connected to or carries the contact 8. For convenience, said contacts 6 and 6^a may be referred to as the east-bound 70 block-closing contacts and the contacts 6^c and 6^d may be referred to as the east-bound block-clearing contacts. The contacts 6^f and 6^g may, for convenience, be referred to as the west-bound block-closing contacts. 75 Positioned in or adjacent to said section C are the normally open contacts which may, for convenience, be referred to as the west-bound block-clearing contacts 6^h and 6ⁱ, which contact 6^h is electrically connected in any suitable manner or by any suitable 80 means with the conductor 11, or the corresponding pole of said source E, as preferably by a wire 6^j and said contact 6 and said wire 7. The contact 6ⁱ is electrically connected by any suitable means, as preferably by the wire 6^k and a portion of said wire 14, with the battery-connected end of said coil. Said section A is electrically connected in any suitable manner and by any suitable 85 means including a normally open contact, as by the wires 15 and 15^a and the contact points 15^b, 4^a, and the wire 4, respectively with said sections C and C¹.

While we describe the use of certain wires, 95 portions of some of which are at one time included in one circuit and another time in another circuit, it will be obvious to any one skilled in the art that the same operations might be effected by providing separate conductors for certain purposes, as, for example, said wires 4 and 5 might each be divided and separate or duplicate contacts similar to 4^a and 5^a might be provided to electrically connect the section A with the section C through one of the resulting halves of each of said wires 4 and 5 and to separately connect the section A² with the section C¹ through the other one of the resulting halves of each of said wires 4 and 5, the operative result being 100 the same as in the case of a part of the single wire 5 and connections performing a service at one time for one end of the block and at another time for the opposite end thereof. We do not therefore desire to limit ourselves 105 to the exact arrangements of our conductors as shown but regard any variation of such arrangements which does not materially affect the characteristic features or operations of our invention as being within the spirit and 110 scope thereof.

It will be observed that the insulation blocks are preferably so spaced that at no time may the blocks 1^b and 1^c or 2^b and 2^c or 1^f and 1^g or 2^f and 2^g intervene at any one time between the circuit terminals represented by said trucks, or between the points of said forward and rearward trucks demarking the full track-contacting length of said conveyance.

As illustrated, the contacts 6 and 6^a are preferably transversely opposite to the contacts 6^h and 6ⁱ and are alined with the contacts 6^c and 6^d and are diagonally opposite the contacts 6^f and 6^g; and the contacts 6^c and 6^d are preferably transversely opposite to the contacts 6^f and 6^g, and the latter contacts are alined with the contacts 6^h and 6ⁱ; but this exact arrangement is not in all respects essential but depends to some degree on the position, or adjustability or construction of whatever means may in practice be employed to close said contacts. Said last referred to eight contacts are also preferably laid or positioned in the road bed between said lines of rails and within said sections C and C¹ respectively, as suggested by the drawings; but this arrangement is not in all respects essential, since they may be supported by any suitable means or in any suitable manner, as the side of the track, or upon overhead brackets, or otherwise as desired, depending to a degree upon the position, or adjustability or construction of whatever means may in practice be employed to close said contacts. It is to be observed also that said wires, rails or contacts are respectively properly insulated by any sufficient means or in any manner from electrical communication with any conductor with which they are not intended to electrically connect or from any conductor which would prevent the operation designed for them to perform. Under certain circumstances the contacts 6^f, 6^g, 6^h and 6ⁱ may if desired be omitted, as when said construction is to be availed of only by conveyances passing in one direction upon said rails, as from west to east, returning on another track.

The construction thus far described, exclusive of a conveyance on said rails, is regarded by us as a complete workable device, equipment or apparatus adapted for any use to which it may be put, and adapted to be operated by whatsoever means may be capable of operating it, one of which uses and one of which means for operating it we will now describe.

Referring again to the drawings, 16 represents a locomotive moving on said lines of rails and equipped with an electrical apparatus hereinafter described and which may therefore be called a traveling, or carried electric apparatus or circuit. Said locomotive may be driven by any of a variety of means, as by an electric motor or by steam-operated mechanism (not shown), of any suitable construction, and in any of the well known ways. The forward truck of said locomotive in the particular construction illustrated is insulated from the rear truck thereof in any suitable manner or by any suitable means, as at 17. Electrically connected to the supporting wheels of said forward truck, by any suitable means, prefer-

ably including the wire 18, is one pole of a suitable source of electricity carried by said conveyance, as the battery G, the opposite pole of which is electrically connected with the supporting wheels of said rear truck by 70 any suitable means preferably including the wire 19. For the purposes of said carried circuit, however, said trucks only represent one of several available forms of forward and rearward circuit-closing or track-contacting terminals for said wires 18 and 19 each adapted to contact with both of said lines of rails. Said circuit is adapted to be normally closed by the rails or one of the rails or a portion thereof upon which said 75 trucks stand or run. Carried by said locomotive and interposed in the circuit which includes said source G is an electrically operated signal-receiving device or devices of any suitable nature adapted to have some suitable and desired influence upon the mechanism of said locomotive or upon the operator thereof, as, for example, a safety-signal lamp 20 and an electro-magnet 21, which magnet is adapted, for example, to hold in 80 valve-opening position a steam-valve stem, 22 or in circuit-closing position the circuit-closing lever, similarly constructed, of an electric circuit including a motor for driving said conveyance, which lever in either case 85 may constitute the armature, or be carried by the armature of said electro-magnet 21 and adapted when released by said magnet to be retracted to steam-valve-closing or electric-circuit opening position, as the case may 90 be, by a counter-balance weight or spring 23. If desired said lever, or another lever similarly held might be so arranged as when retracted to set an air brake, thus further controlling said locomotive. Carried by said 95 locomotive is a brush or shoe or bridging contact 24 preferably insulated from said locomotive and adapted when said locomotive is running forward in one direction to contact first with said contacts 6 and 6^a and after 100 leaving the latter said contacts to contact, if the locomotive proceed far enough, with said contacts 6^c and 6^d, and when running forward in the opposite direction to contact first with said contacts 6^f and 6^g, and after leaving 105 said contacts, if the locomotive proceed far enough, to contact with said contacts 6^h and 6ⁱ. Said shoe may, if desired, be transversely movable and so connected with the reverse-lever of the locomotive that when 110 said locomotive is running backward the shoe will be shifted from its normal position to a position in which it may still engage suitable pairs of said block-closing and block-opening contacts; or separate such shoes may be provided and raised or lowered to suitable position, according as said locomotive is running 115 forward or backward. If desired the track-contacting terminals of said carried circuit 120 may be some other suitable means than said 125 130

truck-supporting wheels; in either case, however, said terminals are each longer than any of said insulation blocks 1^b, 2^b, 1^c, 2^c, 1^f, 2^f, 1^g or 2^g.

5 In the operation of the form of our invention illustrated in Fig. 1, while the locomotive is wholly on the section A, the circuit from said battery G will be completed through the lamp 20, the electro-magnet 21, 10 the forward and rearward said trucks and a portion of the rails, or of a rail, of said section A. When said forward truck, or its equivalent circuit-terminal straddles or spans said insulation blocks 1^b and 2^b, said circuit from 15 said battery G will still be completed as last above referred to or else the current will be diverted so as to flow from said battery G through said forward truck or terminal to a rail of section C, thence through the wire 4, 20 thence through the contacts 4^a and 5^a, thence through a portion of the wire 5 and rail of section A, the rear truck and electro-magnet 21 and lamp 20 back to said battery G, or oppositely. When the forward truck 25 rests entirely on said section C and the rear truck on section A the circuit from said battery G will flow as last above referred to. When said locomotive is entirely on said section C the circuit from said battery G will be 30 closed between the trucks by a rail or rails of said section C. At this time said shoe 24 will close the circuit between said contacts 6 and 6^a, thus closing the circuit from said battery E through the electro-magnet F, a portion of 35 the wire 12, the contacts 6^a, the shoe 24, the contact 6, the wire 7 and part of the wire 12 back to said battery E, thus energizing said electro-magnet F, which thereupon attracts said armature 10, breaking the connection 40 between contacts 4^a and 5^a and establishing electrical connection between said contacts 4^a and 15^b and also between said contacts 8 and 9, thus closing a circuit from said battery E through the wire 11, the contact 9, 45 the contact 8 and the coil of said electro-magnet F which last said circuit maintains the energy of said electro-magnet until the current is short-circuited away from said electro-magnet as hereinafter described. Now 50 when said locomotive passes to a position straddling or spanning said insulation blocks 1^c and 2^c the current from said battery G will flow from the forward truck to a rail of section A¹, thence through a portion of the wire 15 and the wire 15^a and the contacts 15^b and 4^a and a portion of the wire 4 and a rail of 55 said section C to said rear truck and thence through the electro-magnet 21 and lamp 20 back to said battery G. When said locomotive moves wholly on to said section A¹, said 60 current will flow from one to the other of said trucks directly through a rail of said section A¹, and such flow will be preserved until said locomotive arrives in a position straddling said insulation blocks 1^f and 2^f when

the current from said battery G will flow from said forward truck to a rail of said section C¹, thence through a portion of the wire 4 and the contacts 4^a, 15^b and the wire 15^a and a portion of the wire 15 to a rail of said section A¹ and thence to said rear truck and, as before, back to said battery G. When said locomotive is wholly upon said section C¹ the current from said battery G flows directly through a rail of said section C¹ from the forward to the said rear truck. At, or about the time when said locomotive moves wholly on to said section C¹, the shoe or bridging contact 24 contacts with said contacts 6^c and 6^d, closing said contacts and thus short-circuiting the current from said battery E away from said electro-magnet F through the wire 14, contact 6^c, shoe 24, contact 6^d, wire 13, contact 6, wire 7, and part of the wire 11, thereby deenergizing said electro-magnet F, which thereupon drops its armature, breaking the connection between contacts 8 and 9 and between contacts 4^a and 15^b and establishing electric connection between contacts 4^a and 5^a. Now when said 90 conveyance moves to a position astride of said insulating blocks 1^g and 2^g the currents from said battery G will flow from the said forward trucks to a rail of said section A², thence through a portion of said wire 5 and through contacts 5^a and 4^a and a portion of the wire 4, a rail of section C¹, to said rear truck and thence as before back to said battery G. When said locomotive straddles said insulation block 2^h or moves wholly on to said section A² the current from said battery G will flow from said forward truck directly through a rail of said section A² to said rear truck.

The operations heretofore described indicate and presuppose a clear track in front of said locomotive on the sections C, A¹, and C¹. If while said conveyance is on said section A¹ a second conveyance similarly equipped attempts to cross either of said sections C or C¹ going toward said section A¹, the current from said battery G on said second conveyance will usually under such conditions be interrupted the moment the forward truck of said second conveyance passes the insulation blocks 1^b and 2^b, or 1^g and 2^g, as the case may be, for the reason that at such time under such conditions no electrical connection will usually exist between said sections A and C or between said sections A² and C¹. The safety signal lamp on said second conveyance will therefore be extinguished and the valve-closing, or switch-opening lever held by the electro-magnet 21 on said second conveyance will be released. This may be termed the danger signal and indicates the occupancy of the block A¹ by the first said conveyance or locomotive. If, however, because of some defect or failure in the apparatus, the magnet F failed to 130

become or remain energized after the contact of the shoe on the first conveyance or locomotive with said contacts 6 and 6^a, the second or third conveyance would get no signal upon its forward truck passing wholly on to said section C or C¹ respectively, even though said first conveyance still occupied said section A¹; but the current from the battery carried by said second or third conveyance would in such case be interrupted the moment that the whole of its forward truck passed over said insulation blocks 1^c and 2^c or over said insulation blocks 1^f and 2^f as the case might be, for the reason that because said magnet F failed its armature would not at such time be lifted or electrical connection established through said contacts 4^a and 15^b from said section C to said section A¹, or from said section C¹ to said section A¹. The safety signal lamp 20 on said second conveyance would thereupon be extinguished and the valve-closing or switch-opening lever held by the electro-magnet 21 on said second conveyance would be released. This may be termed the "fail to danger" signal, meaning that when the primary danger-indicating mechanism becomes defective or fails to perform its office the failure thereof will bring into action other danger-indicating devices which will indicate that the primary danger signaling devices cannot longer be relied upon. The subsequent action of the operator or engineer of said second conveyance will then be as may be prescribed by law or the rules of the road. In like manner when the first conveyance enters upon said section A¹, if said magnet F fails to attract or hold its armature said first conveyance will receive a "fail to danger" signal and the sub-action of its engineer will be as may be in such case prescribed by law or by the rules of the road; or if said magnet F drops its armature or any other sufficient defect in the devices comes into existence while said first conveyance is on said section A¹ said first conveyance will receive a "fail to danger" signal when it enters partly on said section C¹ from said section A¹, and the action of its engineer will thereafter be, in consequence, as in such case prescribed by law or the rules of the road.

If such a locomotive should be running backward on said lines of rails with a properly shifted shoe 24 or if it were turned about and were running forward in the direction opposite to that first described, the action of said invention will be similarly as before, except that in such case the current energizing said magnet F will first flow from one pole of said battery E through the coil of said electro-magnet F, thence through said wire 12, thence through said contact 6^g, thence through said shoe 24, thence through said contact 6^f, thence through said wire 6^e, thence through said contact 6, thence

through said wire 7 and part of said wire 11, to said battery E, when said conveyance thereafter reaches the contact 6^h and 6ⁱ, the block will be cleared by short circuiting the current away from said electro-magnet F from one pole of said battery E through the wire 6^k, thence through said contact 6^l, thence through said shoe 24, thence through said contact 6^h, thence through said wire 6^j, thence through said contact 6, thence through said wire 7 and part of said wire 11 to the opposite pole of said battery E.

While we have referred to the direction of flow of various currents we do not desire to be limited to currents flowing in such directions; the connections may in some instances be transposed within the scope and spirit of our invention, the circuits resulting being equivalent and the operations and results secured being the same. The various contact points or surfaces may within the scope and spirit of our said invention be constructed and supported in any suitable manner or of any suitable material and some of those governed by said armature or armature-lever 10, may embody portions of said armature or armature-lever insulated from other portions thereof or said last referred to contacts may consist as shown of points or contacts carried by said armature or armature-lever but not including any part thereof in circuit.

In Fig. 2 of said drawings, we have illustrated a modified form of our invention adapted for use where the rails are not required to carry a conveyance-driving power-current. In this form of construction the metallic bridge 3^a is omitted, and the contacts 6, 6^d, 6^f and 6^h are preferably included in the lines of conveyance-supporting rails. Since the circuits are in other respects substantially the same as shown in Fig. 1, relatively corresponding parts are indicated by the same reference figures or characters as shown in Fig. 1.

In Fig. 3, we have illustrated a second modified form of our said invention, in which the invention is adapted for operation by a third rail or trolley independent of the supporting rails of such conveyance, in this case no insulations need be used in said supporting rails, and another rail, 3, may be substituted for supporting the conveyance in the place of the rail or trolley 2 thus relieved from such service. The form of our invention shown in Fig. 3 may also be used on a highway for automobiles requiring no conveyance-supporting rails; or if such supporting rails are laid they may be used either to support a steam-driven conveyance, or to carry a driving electric current to an electrically-driven conveyance running on said supporting rails. In this form of our invention if the supporting rails be carrying a conveyance-driving electric current the rail-contacting terminals of the wires 25 and 26 of the traveling circuit

will be insulated in any suitable manner, or by any suitable means from the supporting wheels or supporting rails of said conveyance. In other respects the circuits are substantially the same as shown in Figs. 1 and 2; we have therefore indicated the relatively corresponding parts of the circuits by the same reference numerals or characters as in said Figs. 1 and 2.

10 In Fig. 4, we have illustrated a modified form of construction of the means for discontinuing the electric circuit through the coil of said magnet F, which latter modified construction is applicable within the spirit and 15 scope of our invention to either of the forms of our invention shown in Figs. 1, 2 or 3. This modification affects only the means employed for the deenergization of F, after it has been energized in the manner already 20 described and in no way changes the construction or operation of the signal and safety appliances on the conveyance. This is accomplished by introducing a normally closed circuit-breaking contact k into the electric 25 connection between the said battery or source of electricity E and that end of said coil of said electro-magnet F which is normally connected to said battery, and by introducing an electro-magnet G and a source 30 of electricity H into the normally open circuit between, for example, the points of the contacts 6^h and 6ⁱ. Said electro-magnet G is provided with an armature 16 adapted when operated or attracted to said magnet G 35 to break said normally closed contact k. In such case the wires 6^k and 14 and the contacts 6^c and 6ⁱ will be connected to the coil of said electro-magnet G. When the brush or shoe 24, passing from left to right makes 40 contact between 6 and 6^a, a circuit will be established from battery E, contact K, coil of electro-magnet F, wires 6^b, 6^a, 24, 6 and 7 back to E, which will cause F to attract its armature, closing contacts 8 and 9, and 4^a 45 and 15^b, and opening contacts 4^a and 5^a as hereinbefore described. Now when the contacts 6^c and 6^d, for example, are electrically connected or closed by said traveling contact 24, a circuit will be established from said 50 source H through the coil of said electro-magnet G and the wire 14 and the contact 6^c and the shoe 24 and the contact 6^d and the wire 4 and a portion of the wire 7 and the wire 7^a back to said source H; thus magnetizing said magnet G and causing it to momentarily attract its armature 16 and thereby to momentarily or temporarily break said contact k.

55 In Fig. 5, we have illustrated still another modified form of our invention, in which latter form there is introduced another magnet similar to the first said electromagnet F, and connected in multiple with the first said electro-magnet F through two normally 60 open electro-contacts. This form embodies 65

certain of the circuits of the other forms, and the parts approximately corresponding to said other forms are designated in the same or approximately the same manner.

70 In view of the extended description given of the invention constructed as shown in Fig. 1, it is believed that the brief descriptions of the forms shown in Figs. 2, 3, 4 and 5 will be sufficient to fully disclose the invention as illustrated in the latter four figures to anyone skilled in the art, and that therefore further description thereof will not be necessary.

75 While we have described the above modifications or various forms of our invention we do not desire to be limited to the exact modifications shown or to the exact wiring schemes shown, as it is evident to anyone skilled in the art that further modifications may be made within the spirit and scope of 80 our invention and without departing from the general principles thereof.

85 Having now described our said invention, what we claim and desire to secure by Letters Patent is,

90 1. The combination of a normally open multiple electric circuit of two branches, including a source of electricity, and an electro-magnet common to both said branches and a normally open circuit-controlling contact in each branch of said circuit, one of 95 said open contacts being positioned at one side of an imaginary line and the other of said open contacts being positioned diagonally opposite to the first said contact and 100 on the opposite side of said line; a traveling bridging contact adapted when moving in one direction to temporarily close the first said normally open contact and when moving in the opposite direction to temporarily 105 close the other of said normally open contacts; and a normally open electric circuit including said source of electricity, the coil 110 of said electro-magnet and a normally open contact adapted to be closed when said electro-magnet is energized.

115 2. The combination of a normally open multiple electric circuit of four branches, including a source of electricity common to each of said branches, an electro-magnet 120 common to two of said branches, and a normally open circuit-controlling contact in each branch of said multiple circuit, the open contacts of the electro-magnet-containing branches being positioned diagonally 125 opposite to each other near the corresponding diagonally opposite corners of a parallelogram, and the open contacts of the other two branches being positioned diagonally opposite to each other near the other diagonally opposite corners of said parallelogram, and a traveling bridging contact adapted when proceeding in one direction to first close for a brief period the normally 130 open contact of one of the electro-magnet-

- containing branches of said circuit, and after leaving said contact to close for a brief period the normally open contact of one of said branches in which said electro-magnet
 5 is not included, and when moving in the opposite direction to first close for a brief period the contact of the other of the electro-magnet-including branches of said multiple circuit and after leaving said contact to
 10 close for a brief period the contact of the other of said branches in which said electro-magnet is not included.
3. The combination of a normally open multiple electric circuit of five branches, including a source of electricity common to each of said branches, an electro-magnet common to three of said branches, and a normally open circuit-controlling contact in each of said branches, the normally open
 15 contacts of two of the electro-magnet-containing branches being positioned diagonally opposite to each other along the route of a traveling bridging contact, the normally open contacts of the said branches in which
 20 said electro-magnet is not included being positioned diagonally opposite to each other along said route in such manner that a straight line drawn between them would intersect a straight line drawn between the
 25 first two said diagonally opposite contacts, a traveling bridging contact adapted when traveling in one direction to first close for a brief period the normally open contact of one of the electro-magnet containing said
 30 branches, and subsequently to leaving said contact to close for a brief period the normally open contact of one of said branches in which said electro-magnet is not included; an armature governed by said electro-
 35 magnet and adapted when attracted by said electro-magnet to close the normally open contact of the third electro-magnet-containing branch of said multiple circuit.
4. The combination of a normally open multiple electric circuit of five branches, including a source of electricity common to each of said branches, an electro-magnet common to three of said branches, and a normally open circuit-controlling contact in each of said branches, the normally open said contacts of two of the electro-magnet-containing branches being positioned diagonally opposite to each other along the route of a traveling bridging contact, the normally open
 45 contacts of the said branches in which said electro-magnet is not included being positioned diagonally opposite to each other along said route in such manner that a straight line drawn between them would intersect a straight line drawn between the
 50 first two said diagonally opposite contacts, a traveling bridging contact adapted when traveling in one direction to first close for a brief period the normally open contact of one of the electro-magnet-containing branches of said multiple circuit and when retracted to open or re-open the last said contact.
5. The combination of a normally open multiple electric circuit of two branches including a source of electricity common to each of said branches, an electro-magnet in one of said branches and a normally open circuit controlling contact in each of said branches; and a normally open electric circuit including said source of electricity, the coil of said electro-magnet and a normally open contact adapted to be closed when said electro-magnet is energized.
6. The combination of a normally open multiple circuit of three branches including a source of electricity common to all of said branches, an electro-magnet common to only two of said branches, and a normally open circuit controlling contact in each of said branches; an armature for said electro-magnet adapted when attracted to said electro-magnet to close the normally open contact in one of the electro-magnet-containing branches of said circuit and when retracted to open or re-open the last said contact.
7. The combination of a normally open multiple electric circuit including three branches and including a source of electricity common to each of said three branches, a normally open circuit controlling contact in each of said three branches, an electro-magnet common to two of said branches; an armature for said electro-magnet adapted when attracted by said magnet to close the normally open contact of one of said electro-magnet-containing branches, a traveling bridging contact adapted when proceeding in one direction to first close the normally open contact of the other of said electro-magnet-containing branches, and subsequently to leaving said contact to close for a brief period the normally open contacts of one of said branches in which said electro-magnet is not included; an armature governed by said electro-magnet and adapted when attracted by said electro-magnet to close the normally open contact of the third electro-magnet-containing branch of said multiple circuit; a line of rails or a trolley laid along said route or parallel therewith and electrically divided into sections; a traveling normally closed electric circuit, including a source of electricity, and electrical devices adapted to be operated by electricity flowing therefrom, and rail or trolley-contacting contacts, said traveling circuit being adapted to progressively loop into circuit and be normally closed by, and to progressively drop out of circuit said sections of rails or trolley or portions thereof; a plural number of partial circuits having circuit controlling contacts adapted to be governed by an electro-magnet of said multiple circuit, said partial circuits each having another circuit-controlling contact adapted in relative succession to be closed by, and normally to close and be looped into said traveling circuit.
8. The combination of a normally open multiple electric circuit of two branches including a source of electricity common to each of said branches, an electro-magnet in one of said branches and a normally open circuit controlling contact in each of said branches; and a normally open electric circuit including said source of electricity, the coil of said electro-magnet and a normally open contact adapted to be closed when said electro-magnet is energized.
9. The combination of a normally open multiple circuit of three branches including a source of electricity common to all of said branches, an electro-magnet common to only two of said branches, and a normally open circuit controlling contact in each of said branches; an armature for said electro-magnet adapted when attracted to said electro-magnet to close the normally open contact in one of the electro-magnet-containing branches of said circuit and when retracted to open or re-open the last said contact.
10. The combination of a normally open multiple electric circuit including three branches and including a source of electricity common to each of said three branches, a normally open circuit controlling contact in each of said three branches, an electro-magnet common to two of said branches; an armature for said electro-magnet adapted when attracted by said magnet to close the normally open contact of one of said electro-magnet-containing branches, a traveling bridging contact adapted when proceeding in one direction to first close the normally open contact of the other of said electro-magnet-containing branches, and subsequently to leaving said contact to close for a brief period the normally open contacts of one of said branches in which said electro-magnet is not included; an armature governed by said electro-magnet and adapted when attracted by said electro-magnet to close the normally open contact of the third electro-magnet-containing branch of said multiple circuit; a line of rails or a trolley laid along said route or parallel therewith and electrically divided into sections; a traveling normally closed electric circuit, including a source of electricity, and electrical devices adapted to be operated by electricity flowing therefrom, and rail or trolley-contacting contacts, said traveling circuit being adapted to progressively loop into circuit and be normally closed by, and to progressively drop out of circuit said sections of rails or trolley or portions thereof; a plural number of partial circuits having circuit controlling contacts adapted to be governed by an electro-magnet of said multiple circuit, said partial circuits each having another circuit-controlling contact adapted in relative succession to be closed by, and normally to close and be looped into said traveling circuit.

open contact of the other of said electro-magnet-containing branches and after leaving and re-opening the same to close the normally open contact of the one of said branches which does not include said electro-magnet.

8. The combination of a normally open electric circuit including a source of electricity, the coil of an electro-magnet and a normally open circuit-controlling contact; a normally open second electric circuit, including a source of electricity, the coil of an electro-magnet and a normally open circuit-controlling contact; an armature governed by the electro-magnet of said second circuit and adapted to be operated thereby to close the normally open contact of said second circuit when the normally open contact of the first said circuit is closed; a partial circuit including a normally closed circuit-controlling contact adapted to be opened or broken by the operation of said armature when said armature is attracted toward its governing electro-magnet, and a normally open circuit-controlling contact; a second normally open partial circuit, including a normally open circuit-controlling contact and a second normally open circuit-controlling contact, the last said contact being adapted to be closed by the operation of said armature when said armature is attracted toward its governing electro-magnet; means for momentarily or for a brief period closing and subsequently re-opening the normally open contact of the first said circuit; means including a normally open circuit-controlling contact normally adapted when the last above said contact is closed to discontinue the flow of the electric current through the coil of the electro-magnet of the second said electric circuit, and means adapted to momentarily or for a brief period close the last said contact.

9. The combination of a normally open electric circuit including a source of electricity, the coil of an electro-magnet and a normally open circuit-controlling contact; a normally open second electric circuit including a source of electricity, the coil of an electro-magnet, and a normally open circuit-controlling contact; an armature governed by the electro-magnet of said second circuit and adapted to be operated thereby to close the normally open contact of said second circuit when the normally open contact of the first said circuit is closed; a partial circuit including a normally closed circuit-controlling contact adapted to be broken by the operation of said armature when said armature is attracted toward its governing electro-magnet, and a normally open circuit-controlling contact; a second normally open partial circuit including a normally open circuit-controlling contact and a second normally open circuit-controlling contact, the last said contact being adapted to be closed by the operation of

70 said armature when said armature is attracted toward its governing electro-magnet; a normally open third electric circuit electrically connected at one end to that end of the said coil of said second circuit which is normally or permanently connected to the source of electricity of said second circuit, the opposite end of said third circuit being electrically connected to the opposite pole of the last said source, said third circuit including a normally open contact; a traveling contact adapted when moving in one direction to first temporarily or for a brief period close the normally open contact of the first said circuit, and after leaving said contact to subsequently temporarily or for a brief period close the said normally open contact of said third circuit; a traveling normally closed electric circuit including a source of electricity adapted when moving in one direction to temporarily loop in and close the first said partial circuit when said armature is in retracted position, and subsequent to dropping out the first said partial circuit, to temporarily loop in and close and be closed by the second said partial circuit when said armature is attracted to its governing magnet; a series of contacts including the normally open contacts of the first said partial circuit and the first said normally open contacts of the said second partial circuit and other contacts adapted normally to successively close said traveling circuit.

10. The combination of a normally open electric circuit including a source of electricity, the coil of an electro-magnet and a normally open circuit controlling contact; a normally open second electric circuit, including a source of electricity, the coil of an electro-magnet and a normally open circuit controlling contact; means governed by the electro-magnet of said second circuit adapted, when the normally open contact of the first said circuit is closed, to close the normally open contact of said second circuit; a partial circuit including a normally closed circuit-controlling contact and a normally open circuit-controlling contact; means governed by the electro-magnet of said second circuit adapted when operated to open the normally closed contact of said partial circuit; a second normally open partial circuit including a normally open circuit-controlling contact and a second normally open circuit controlling contact; means governed by the electro-magnet of said second circuit and adapted to temporarily close the said second normally open contact of said second partial circuit when said electro-magnet of said second circuit is energized; means adapted to momentarily or for a brief period close the normally open contact of the first said circuit; electrically operated means including a normally open circuit-controlling contact and normally adapted when the last said con- 130

- tact is closed to discontinue the flow of electricity through the coil of the magnet of the said second circuit, and means for temporarily closing the last said contact; a normally closed traveling electric circuit including a source of electricity and a signal device or valve-governing means adapted when proceeding in one direction to first for a brief period loop in and close and be closed by the 5 first said partial circuit when the normally closed contact of the first said partial circuit is closed and after dropping out the first said partial circuit to subsequently loop in and close and be closed by the second said partial circuit when the said second normally open contact of said second partial circuit is closed; a series of contacts, including the normally open contacts of the first said partial circuit and the first said normally open 10 contacts of the said second partial circuit and one or more relatively independent contacts normally adapted to be each successively for a brief period looped into and in turn to close and maintain said traveling circuit.
- 15 11. The combination of a normally open electric circuit, including a source of electricity, the coil of an electro-magnet and a normally open circuit-controlling contact; a second normally open electric circuit including a source of electricity an electro-magnet and a normally open circuit-controlling contact; an armature governed by the electro-magnet of said second circuit and adapted when operated to close the normally open 20 contact of said second circuit; a partial circuit including a normally open circuit controlling contact adapted to be closed by said armature when said armature is attracted toward its said governing electro-magnet, 25 and a second normally open contact.
- 20 12. The combination of a plural number of partial circuits each having a normally open circuit-controlling contact including two mutually contiguous points or rails each of 30 which points or rails separately in whole or in part, and each pair of said points or rails as elements of the respective said partial circuits is adapted to be in relative succession looped into a traveling circuit to normally 35 close said circuit and to be each in relative succession dropped out of said traveling circuit as the relatively succeeding said points or rails or pairs thereof are looped into said circuit, the first of said partial circuits including a normally closed circuit controlling contact, the second and third of said partial circuits each including a second normally open circuit controlling contact and the fourth of 40 said partial circuits including a normally closed circuit controlling contact; means including a traveling contact adapted to open the normally closed contact of the first said partial circuit after said partial circuit has been dropped from said traveling circuit and 45 simultaneously to close the said second nor-
- 50 mally open circuit-controlling contacts of the second and third said partial circuits and to simultaneously open the normally closed circuit-controlling contact of said fourth partial circuit, and means including a traveling 55 contact adapted to open the second normally open contacts of each of said second and third partial circuits after the said third partial circuit has been dropped from said traveling circuit, and simultaneously to close the 60 normally closed circuit-controlling contact of said fourth partial circuit.
- 55 13. The combination of a normally open electric circuit including a source of electricity, the coil of an electro-magnet and a normally open circuit controlling contact; a second normally open electric circuit, including a source of electricity, the coil of an electro-magnet and a normally open circuit-controlling contact; an armature governed by the 65 electro-magnet of said second circuit and adapted normally to be operated by its governing electro-magnet to close the normally open contact of the said second circuit when the normally open contact of the first said circuit is closed; a partial electric circuit comprising a normally open circuit-controlling contact governed by said armature and adapted to be closed thereby when said armature is attracted toward its said governing 70 electro-magnet, and electric conductors extending from the opposite points of the last said normally open contact and provided at their outer ends with mutually contiguous normally open circuit-controlling contacts; a 75 conveyance; a normally closed electric circuit partly carried thereby and including a source of electricity and devices to be operated by electricity flowing from the last said source, and rail or trolley-contacting contacts; a conductor or conductors of electricity adjoining said conveyance and forming a line of rails or a trolley, electrically divided into sections and including both of the outward contacts of said partial circuit and 80 adapted normally to be progressively looped in and dropped from said carried circuit; means carried by said conveyance adapted to close the normally open contact of the first said circuit before said conveyance has 85 reached the position where both or portions of each of said outward contacts of said partial circuit are included in the circuit partly carried by said conveyance.
- 80 14. The combination of a normally open 90 electric circuit, including a source of electricity, the coil of an electro-magnet and a normally open circuit-controlling contact; a second normally open electric circuit, including a source of electricity, the coil of an electro-magnet and a normally open circuit-controlling contact, an armature adapted to be governed by the electro-magnet of said second circuit and adapted normally to be operated 95 by its said governing magnet to close the 100

normally open contact of said second circuit when the normally open contact of the first said circuit is closed; a partial electric circuit including a normally closed circuit-controlling contact governed by said armature and adapted to be opened thereby when said armature is attracted toward its governing electro-magnet, electric conductors extending from the opposite points of said normally 10 closed contact and provided at their outward ends with mutually contiguous normally open circuit controlling contacts; a conveyance; a normally closed electric circuit partly carried by said conveyance and including a 15 source of electricity, devices to be operated by electricity flowing from the last said source, and rail or trolley-contacting contacts; a conductor or conductors of electricity adjoining said conveyance and forming a 20 line of rails or a trolley, electrically divided into sections and including both of the outward contacts of said partial circuit, and adapted normally to be progressively looped into and dropped from said carried circuit; 25 means carried by said conveyance adapted to close the normally open contact of the first said circuit after said conveyance has reached a position where both of said outward contacts of said partial circuit have been included in the circuit partly carried by said 30 conveyance.

15. The combination of a temporarily closed electric circuit including a source of electricity, the coil of an electro-magnet 35 and a temporarily closed circuit-controlling contact; a partial electric circuit including a temporarily closed circuit-controlling contact governed by the electro-magnet of said temporarily closed electric circuit and 40 adapted to effect the discontinuance of the flow of electricity through the coil of said electro-magnet; conductors of electricity extending from the opposite points of the temporarily closed contact of said partial circuit and provided at their outward ends 45

with mutually contiguous normally open circuit controlling contacts; a conveyance; a normally closed electric circuit partly carried thereby and including a source of electricity and devices adapted to be operated 50 by electricity flowing therefrom, and rail or trolley-contacting contacts; electric conductors adjoining said conveyance and forming a line of rails or a trolley electrically divided into sections and including both of the 55 outward contacts of said partial circuit and adapted normally to be progressively looped into and to close said partly carried circuit and to be progressively dropped therefrom; and means adapted to be operated in part by said conveyance to discontinue the flow of electricity in the coil of the first said electro-magnet after the outward contacts or either of them of said partial circuit have been dropped from said partly 60 carried circuit.

16. A multiple electric circuit, including a source of electricity common to each of three branches, the coil of an electro-magnet common to two of said branches, a separate 70 normally open circuit controlling contact for each of said branches, a traveling bridging contact adapted to close the normally open contact of one of said branches in which said electro-magnet is included and 75 subsequently to leaving and re-opening the latter said contact to close the normally open contact of the branch in which said electro-magnet is not included; and means governed by said electro-magnet adapted to 80 close the normally open contact of the other electro-magnet-containing branch while said electro-magnet is energized.

In testimony whereof we hereunto affix our signatures, in presence of two witnesses. 85
